UNITED STATES PATENT OFFICE.

WILLIAM H. LEONARD AND OMAR E. CLARK, OF DENVER, COLORADO, ASSIGNEES TO
THE DENVER ROCK DRILL MANUFACTURING COMPANY, OF DENVER, COLORADO,
A CORPORATION OF DELAWARE.

LUBRICATOR FOR ROCK-DRILLS.

1,177,713.

Specification of Letters Patent.

Patented Apr. 4, 1916.

Application filed April 27, 1915. Serial No. 24,259.

To all whom it may concern:

Be it known that we, WILLIAM H. LEONARD and OMAR E. CLARK, citizens of the United States, residing at Denver, in the county of Denver and State of Colorado, have invented new and useful Improvements in Lubricators for Rock-Drills, of which the following is a specification.

The present invention relates particularly to means for lubricating the movable parts of a motor, and especially a rock drill, and the object is to provide improved means whereby the lubricant will be effectively vaporized and delivered by the motive fluid to ail parts of the machine.

An embodiment of the invention that has proven satisfactory, is illustrated in the accompanying drawings, wherein:—

Figure 1 is a longitudinal sectional view through a portion of a rock drill, showing the improved lubricator in place therein. Fig. 2 is a cross sectional view on the line 2—2 of Fig. 1 and on an enlarged scale. Fig. 3 is a detail sectional view at right angles to Fig. 2.

Similar reference numerals designate corresponding parts in all the figures of the drawings.

In the embodiment disclosed, the motor includes a cylinder member which comprises a barrel 4 and a rear head 5. In the barrel is a reciprocating piston 6 having an internal constant pressure chamber 7 and a reduced forwardly extending hammer section 8 that operates upon a drill bit 9. This drill bit is placed in a chuck 10 which is rotated from the piston by suitable mechanism, indicated at 11. The fluid under pressure delivered to the constant pressure chamber 7 is distributed to opposite ends of the piston by suitable ports 12 and the reduced hammer extension 8, has a conduit or channel 13 for delivering a portion of the fluid to the bore 14 of the drill bit, for the purpose of cleansing the drill hole.

Interposed between the barrel 4 and the head 5 is a lubricant reservoir designated generally by the reference numeral 15, said reservoir having end walls 16 and 17 and outer and inner tubular walls 18 and 19 forming a lubricant holding chamber 20. Extending through the inner tubular wall from the rear head is a supply tube 21 for

fluid under pressure, said tube projecting into the constant pressure chamber 7, and receiving the fluid supply by means of a channel 22 communicating with the rear end of the tube and also in communication with a suitable coupling 23 by which a hose connected with any suitable source of fluid under pressure may be attached to the machine.

It will be noted that a portion of the inner tubular wall 19 is spaced from the tube 21 forming an annular pocket in which is placed a body of absorbent material 24, such as wicking or the like. A plurality of annular rows of ports 25 are formed in the inner wall 19, and thus afford communication between the lubricant holding chamber 20 and the pocket. A row of ports 26 is formed in the rear end of the tube 21 extending forwardly and outwardly and being in communication with the rear end of the pocket that holds the absorbent material 24. One or more additional ports 27 in advance of the ports 26 are formed in the tube 21 and also communicate with the pocket. Access to the lubricant holding chamber 20 is secured through a port 28 normally closed by a removable plug 29 and a cylindrical screen 30 may be placed in the inner portion of the chamber 20 around the ports 25.

The operation of this device is dependent upon the rise and fall of the pressure of the motive fluid in the constant pressure chamber and the supply tube 21 due to the rapid backward and forward movement of the piston. This rise and fall of the pressure causes the pulsation of the air through the two sets of channels or ports between the tube 21 and the lubricant holding chamber 20. The pulsation of fluid into and out of the chamber 20 tends to vaporize the oil, so that a uniform supply of lubricant permeates every part of the drilling mechanism. Demonstration has shown that the rotating mechanism is thoroughly lubricated as is the piston, and that such is not the case if the lubricant is introduced in liquid form.

From the foregoing, it is thought that the construction, operation and many advantages of the herein described invention will be apparent to those skilled in the art, without further description, and it will be understood that various changes in the size, shape, proportion and minor details of con-

22
struction may be resorted to without departing from the spirit or sacrificing any of the advantages of the invention.

Having thus fully described our invention, what we claim as new and desire to secure by Letters Patent, is:—

1. In apparatus of the character set forth, the combination with a motor comprising a cylinder member and a piston operating therein, of a lubricant reservoir having an inner and an outer wall, a fluid supply conduit for the motor extending alongside the inner wall, an absorbent element interposed between the wall and conduit, and ports through said wall and conduit at said element.

2. In apparatus of the character set forth, the combination with a motor comprising a cylinder member and a piston operating therein, of a lubricant reservoir having an inner and an outer wall, a fluid supply conduit for the motor extending alongside the inner wall, an absorbent element interposed between the wall and conduit, and angularly disposed ports through said wall and conduit at said element.

3. In apparatus of the character set forth, the combination with a motor comprising a cylinder member and a piston operating therein, of a supply conduit for said motor, a lubricant reservoir surrounding the conduit, and a body of absorbent material interposed between the reservoir and supply conduit, said reservoir having ports leading to the absorbent material, and said conduit having ports leading from the absorbent material.

4. In apparatus of the character set forth, the combination with a motor comprising a cylinder member and a piston operating therein, of a supply conduit for said motor, a lubricant reservoir surrounding the conduit, and a body of absorbent material interposed between the reservoir and supply

45 conduit, said reservoir having ports leading to the absorbent material and said conduit having ports leading from the absorbent material and communicating with the bore thereof at different points longitudinally of the conduit.

50 5. In apparatus of the character set forth, the combination with a motor comprising a cylinder member and a piston operating therein, of a supply conduit for said motor, a lubricant reservoir having an inner tubular wall through which the conduit passes, said wall and conduit having portions spaced apart, forming a pocket, and absorbent material located in the pocket, said inner wall and conduit having ports communicating with the pocket.

55 6. In apparatus of the character set forth, the combination with a cylinder member comprising a barrel and a rear head, of a piston operating in the cylinder member and having an internal constant pressure chamber, means for distributing fluid under pressure therefrom, a lubricant reservoir interposed between the barrel and head and having an outer and an inner tubular wall, a supply tube for fluid under pressure extending from the rear head through the inner wall and into the constant pressure chamber, said inner wall and tube having portions spaced apart forming a pocket, and a body of absorbent material located in the pocket, said inner wall and tube having sets of ports, the ports in the tube being disposed at different points longitudinally along said tube.

70 75 80 In testimony whereof we have hereunto set our hands in presence of two subscribing witnesses.
